ELECTRIC HEATER

Edward W. Phillips, Flint, Mich.

Application March 17, 1937, Serial No. 131,485

5 Claims. (Cl. 219—39)

The device forming the subject matter of this application is adapted to be used, primarily, for heating the air of a room. The air to be heated is forced through a radiator, containing a liquid, which, in turn, is heated. The invention aims to provide novel means whereby the air may be drawn, wholly or in part, from the floor of the room, it being possible to shift the point of air inlet to a place above the floor of a room. Another object of the invention is to provide a device of the class described in which neither the air nor the liquid in the radiator will be chilled at starting. A further object of the invention is to supply a novel means whereby access may be had to working parts which need adjustment or repair.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in front elevation, a heater constructed in accordance with the invention;

Fig. 2 is a rear elevation of the heater;

Fig. 3 is a horizontal section on the line 3—3 of Fig. 6;

Fig. 4 is a vertical section on the line 4—4 of Fig. 5;

Fig. 5 is a vertical section on the line 5—5 of Fig. 4;

Fig. 6 is a vertical section on the line 6—6 of Fig. 5.

The device forming the subject matter of this application comprises a housing which may be made in various ways, without departing from the spirit of the invention. The housing may embody a box-like base 1, which is open at the top. The base 1 carries castors 2 whereby the heater may be trundled about readily from one place of use to another. In the bottom of the base 1 (Fig. 3) there is an opening 3. Referring to Fig. 5, it will be seen that a horizontal baffle 4 is disposed below the opening 3 in the bottom of the base 1. The baffle 4 comprises a sheet 5 of heat insulating material, preventing the heat from the

heaters 55 (hereinafter described) from striking downwardly to the floor of the room. At its forward edge, the baffle 4 has an upstanding flange 6 (Fig. 5) which is secured at 7 to the bottom of the base 1. As can be seen in Fig. 3, there are air inlet openings 9 in the bottom of the base 1, in front of the flange 6 of the baffle 4.

The housing comprises a box-like casing 10 having handles 11 on its top. The casing 10 is open at the bottom and receives the base 1. In the front wall of the casing 10 (Fig. 1), there is an opening 12, across which extends a screen or grill 14 secured to the front wall of the casing. The lower portion 100 of the back wall of the casing 10 is fixed, but the back wall of the casing includes a closure 15 (Figs. 2 and 5) which is hinged at 16 to the rear edge of the top of the casing 10, the construction being such that the closure can be opened to give access to mechanism within the housing. A latch 17 on the fixed lower part 100 of the rear wall of the casing 10 engages the lower portion of the hinged closure 15, to hold it closed. In the closure 15 there are air inlet openings 18, controlled by a rotatable damper 19 connected to the closure 15 by a pivot element 20. The damper 19 has a rearwardly projecting handle 21, extended through one of the openings 18 and constituting means whereby the damper 19 may be operated to close the openings 18, or to uncover them more-or-less. The damper 19 works behind a screen 22 (Fig. 5) secured to the closure 15 beyond the periphery of the damper 19.

As shown in Fig. 5, a radiator 23 of any desired construction is located within the casing 10, at the front thereof, and closely adjacent to the screen or grill 14. The radiator 23 has a backwardly prolonged upper tank 24, which extends entirely across the radiator structure, from side to side, as disclosed in Fig. 4. The radiator 23 has a similar backwardly prolonged lower tank 25 (Fig. 5). The filling means 26 for the upper tank 24 extends upwardly through an opening in the top of the casing 10.

The radiator 23 is provided with backwardly extended side walls 27 (Figs. 3 and 5), connected to the ends of the tanks 24 and 25. The side walls 27 are supplied at their upper ends with inwardly projecting flanges 62 (Fig. 6) which engage the top of the casing 10 and support the casing. The side walls 27 of the radiator widen as they extend downwardly, as shown in Fig. 5 and are provided on their rear edges with inwardly projecting flanges 128 which terminate adjacent to the top of the lower tank 25. The side

walls 27 extend downwardly below the lower tank 25, and are provided at their lower edges with inwardly projecting feet 28 (Figs. 6 and 5) which engage the bottom of the base 1 of the radiator housing, and, thus, the radiator is supported in the base 1 of the housing. A sheet 29 of heat insulating material may be secured to the upper surface of the lower tank 25, as shown in Fig. 5, and heat insulating material may be employed wherever considered desirable or necessary.

An overflow receptacle 30 (Figs. 5 and 4) is supported by the lower tank 29 and is located at one side of the casing 10. An overflow tube 31 extends downwardly into the overflow receptacle 30 from the upper tank 24. Outwardly bowed delivery pipes 32 (Figs. 4 and 6) are joined to and communicate with the lower tank 25, the upper ends of the delivery pipes being connected to and in communication with the upper tank 24. The return pipes 32 are adequately jacketed, as indicated at 33, to prevent radiation from them.

The radiator 23 includes a rear wall 34 (Figs. 4, 5 and 6), extended between the side walls 27 and between the upper tank 24 and the lower tank 25. To the rear wall 34, and opening therethrough, is secured a backwardly prolonged tubular sleeve 35, the axis of which is horizontal. The sleeve 35 extends rearwardly to a point closely adjacent to the closure 15 which forms part of the rear wall of the casing 10, as seen in Figs. 5 and 2. The ends of a horizontal upper sustaining bar 36, and the ends of a horizontal lower sustaining bar 37 (Fig. 4) are secured to the side walls 27 of the radiator 23. In their intermediate portions, the sustaining bars 36 and 37 are connected by securing elements 38 to the tubular sleeve 35, the lower bar 37 being disposed at some distance to the rear of the upper bar 36, as Fig. 5 will make manifest. Notches 40 are formed in the rear end of the sleeve 35 (Fig. 5) and the material freed in the formation of the notches 40 is turned outwardly to form ears 41 (Fig. 4). A motor support 39, in the form of a bar, is seated in the notches 40, and has its ends connected to the ears 41 by securing devices 42.

An electric motor 43 (Figs. 4 and 5) is disposed within the tubular sleeve 35, and the rear end of the motor 43 is secured at 44 to the supporting bar 39. The shaft of the electric motor 43 carries a suction and blast fan 45, disposed within the sleeve 35 and located closely adjacent to the radiator 23 (Fig. 5). At its rear end, and in its lower portion, the tubular sleeve 35 is cut away, as seen at 46, to form an opening whereby air proceeding upwardly from the bottom of the housing, as hereinafter described, may find a ready entrance into the sleeve 35.

A slide or drawer, disposed horizontally below the lower tank 25, is provided, and includes a base plate 47 (Fig. 5). The base plate 47 is supplied with a large elongated opening 48, shown in Fig. 3. The base 47 of the slide has depending side flanges 49 (Figs. 5 and 6) which ride slidably on the inwardly projecting feet 28 of the side walls 27 of the radiator 23. At its forward end, the base 47 of the slide has a depending forward flange 50. At the rear edge of the base 47 of the slide there is an upstanding rear flange 51 (Figs. 5 and 4) which has a forwardly extended lip 52, adapted to overlap the rear portion of the top of the lower tank 25. A bracket plate 53 is secured to the flange 51 of the slide and extends downwardly below the base plate 47 of the slide. In

the bracket plate 53, a plurality of insulating thimbles 54 are mounted.

Electrical heaters 55 (Figs. 3, 6 and 5) are secured at 56 to the upper surface of the base 47 of the slide, and have depending terminals 57, extended downwardly through the opening 48 in the base of the slide. The circuit conductors 58 for the heaters are connected to the terminals 57 and extend backwardly through the insulating thimbles 54, the said circuit conductors extending upwardly to switches 59, located on the top of the casing 10. The circuit for the motor 43 is marked by the numeral 60, and extends upwardly to a switch 61 on the top of the casing 10.

Either of the heaters 55 may be put into operation by actuating the appropriate switch 59, or both of them may be put into operation at once. Through the instrumentality of the switch 61, the motor 43 may be caused to drive the fan 45, at the will of an operator. The wiring, and the operation of the heaters 55 and the fan 45, relatively to each other, may be arranged as the operator desires, that being a matter which can be determined simply by selecting ordinary commercial switches of various constructions, for installation at some or all of the places designated by the switches 61 and 59.

As to general operation, let it be supposed that the heaters 55 are in operation, and that the motor 43 is driving the fan 45. At the outset, the operator closes the damper 19 of Figs. 2 and 5, so that air cannot enter through the air inlet openings 18, directly into the rear end of the sleeve 35. The air then is drawn upwardly from the floor of the room, about the edges of the baffle 4 of Fig. 5, through the openings 8 in the forward flange 6 which supports the baffle plate, or through the openings 9 (Fig. 3) in the bottom of the base 1. The air passes upwardly through the opening 3 in the bottom of the base 1, and is pre-heated by the heaters 55, the base 47 of the slide being in a heated condition. The air, having been pre-heated, enters the tubular sleeve 35 through the opening 46 of Fig. 5 and is driven by the rotating fan 45 through the radiator 23, where the air is heated chiefly. It is to be observed, again, that the air is pre-heated before it passes through the radiator 23, and, therefore, there is no chilling of the water or other solution, in the radiator 23, at starting.

After the device has been in operation for a little while, or when the operator desires to regulate the temperature, the damper 19 of Figs. 2 and 5 is opened more or less. Then, the air inlet apertures 18 of Fig. 2 are uncovered, wholly or in part, and air, drawn by the fan 45, passes directly through the machine, from front to back. The damper 19 enables the operator to regulate the temperature of the room as occasion may demand. Because the air can be made to enter solely through the opening 3 in the bottom of the base 1 and come into contact with the heated base 47 of the slide on which the heaters 55 are mounted, the cold air is drawn from the floor of the room at starting. As the air in the room becomes heated, down to the floor, it is necessary no longer to draw the air exclusively from the floor, and then the damper 19 may be opened, as hereinbefore described.

The heaters 55 raise the temperature of the liquid in the lower tank 25, the heated liquid rises through the delivery pipes 32 to the upper tank 24. The liquid passes from the upper tank 24 downwardly through the radiator 32 into the lower tank 25, to be heated again. Because the deliv-

ery pipes 32 are thoroughly jacketed, as shown at 33, there is practically no radiation from said pipes, and a corresponding loss of heat is avoided.

As the liquid in the radiator 23 and in the tanks 25 and 24 expands, it may flow through the pipe 31, into the overflow tank 30. The overflow tank 30 requires but little attention because, as the pressure in the tanks 24 and 25 in the radiator 23 is reduced, upon cooling, the liquid is sucked back 10 into the upper tank 24, from the overflow tank 30, through the pipe 31.

Should repairs to the heating system be necessary, the casing 10 may be lifted off the base 1 by means of the handles 11, and the radiator structure 15 and all of the working parts of the device may be lifted out of the base. Then the slide, of which the member 47 of Fig. 5 constitutes a part, may be pulled rearwardly and removed from the radiator structure, access being had easily to the 20 parts of the heating mechanism which are shown in top plan in Fig. 3.

Having thus described the invention, what is claimed is:

1. A device of the class described comprising a 25 housing having an air inlet in its bottom, a radiator combined with the housing, a tank communicating with the lower portion of the radiator, means for heating the tank, the heating means being located below the tank and above the air 30 inlet in the path of the air entering the housing by way of the inlet, means for conducting heated liquid from the tank to the upper portion of the radiator, a sleeve extending backwardly from the radiator and having an opening located within the 35 housing and receiving air derived through the inlet, means under the control of an operator for cutting off the flow of air which passes through the sleeve thereby to facilitate a preheating of the air supply furnished independently by the inlet 40 and the opening, and means for creating a draft of air through the sleeve and through the radiator.

2. A device of the class described comprising a closure movably mounted on the rear wall of the housing, a housing having an air inlet in its lower 45 portion and having side walls, a radiator combined with the housing, a tank communicating with the lower portion of the radiator, means for heating the tank, the heating means being located in the path of the air entering the housing by way 50 of the inlet, means for conducting heated liquid from the tank to the upper portion of the radiator, a sleeve extending backwardly from the radiator to the closure and having means for receiving air derived through the inlet, means under the control of an operator for governing the flow of air which passes through the sleeve independently of the air supply furnished by the inlet, a motor, an air impelling means driven by the motor, and a 55 cross bar secured at its ends to the side walls of the radiator, the cross bar carrying the motor, the sleeve being provided in its rear end with notches

extended backwardly to the closure and receiving the cross bar.

3. A device of the class described comprising a 5 housing having an air inlet in its bottom, a radiator combined with the housing, a tank communicating with the lower portion of the radiator, means for heating the tank, the heating means being located below the tank and above the air inlet in the path of the air entering the housing by way of the inlet, means for conducting heated 10 liquid from the tank to the upper portion of the radiator, a sleeve extended backwardly from the radiator and having an opening located within the housing and receiving air derived through the inlet, means under the control of an operator for 15 cutting off the flow of air which passes through the sleeve thereby to facilitate a preheating of the air supply furnished independently by the inlet and the opening, means housed within the sleeve for creating a draft of air through the sleeve and 20 through the radiator, and a baffle carried by the housing, the baffle extending backwardly beneath the inlet, in vertically spaced relation thereto, to adjust the flow of air into the sleeve by way of the opening and relatively to the air flow governed by 25 the cutting-off means.

4. A device of the class described comprising a 30 housing including a base and a casing telescoped on the base, a radiator in the housing, an upper tank communicating with the radiator, a lower tank 35 communicating with the radiator, the radiator having side walls extended downwardly with respect to the lower tank and supporting the radiator from the bottom of the housing, the upper end of the casing being supported on the upper 40 ends of the side walls, means disposed below the lower tank and between the side walls for heating the lower tank, a conduit connecting the tanks, means for admitting air into the housing, and motor operated mechanism within the housing for 45 impelling air through the radiator.

5. In a device of the class described, a box-like base and a box-like casing disposed thereabove and cooperating with the base to define an enclosing housing, a radiator in the housing and supported 45 removably on the base, the radiator comprising upper and lower tanks, the upper tank supporting the casing, a conduit connecting the tanks, a sleeve secured to and extended backwardly from the radiator to the rear wall of the 50 casing, an air propeller in the sleeve, means carried by the casing and under the control of an operator for admitting a governed supply of air to the sleeve, horizontal guiding means constituting part of the radiator, a slide removably mounted in 55 the guiding means, and a heating means carried by the slide, the base having an air inlet in its bottom and located below the heating means, the sleeve having an air inlet communicating with the interior of the housing, the heating means being 60 disposed below the lower tank.

EDWARD W. PHILLIPS.
